UNITED STATES PATENT OFFICE.

CHARLES H. ANDRUS, OF HARRISBURG, PENNSYLVANIA.

SLIDING DOOR FOR PRESSED-STEEL FREIGHT-CARS.

1,149,319.

Specification of Letters Patent. Patented Aug. 10, 1915.

Application filed June 10, 1914. Serial No. 844,229.

To all whom it may concern:

Be it known that I, CHARLES H. ANDRUS, of Harrisburg, in the county of Dauphin and State of Pennsylvania, have invented 5 certain new and useful Improvements in Sliding Doors for Pressed-Steel Freight-Cars; and I do hereby declare the following to be a full, clear, and exact description of the invention, such as will enable others 10 skilled in the art to which it appertains to make and use the same.

My invention relates to an improvement in sliding doors for pressed steel freight cars, and it consists in the combination and arrangement of parts, and in the details of 15 construction as will be more fully described and pointed out in the claims.

In the accompanying drawings, Figure 1 is a view in side elevation of a section of a 20 freight car showing the doors closed; Fig. 2 is a view in section on the line α α of Fig. 1; Fig. 3 is a view in longitudinal section through the roof at about the longitudinal center thereof, and Fig. 4 is a view in horizontal section taken through the meeting edge of the door.

1 represents the side of a car, 2 the roof, and 3 a side sill secured to the end sills and to the transoms 4 which support the 25 floor 5. The roof is supported at its side edges by the eaves frames (only one of which is shown) each of which is composed of two angle bars 6 and 7, the former of which is L-shaped in cross section and the latter Z 30 shape. The lower flanges of the two angle irons 6 and 7 project toward each other as shown in Fig. 2, but are separated sufficiently for the passage of the upper end of the door 15, and also to provide sufficient space 35 for ventilating the car. These angle irons are secured together by the bolts 9, and are held apart by the spacing sleeves 10, through 40 which the bolts 9 pass, and they are also secured to the side frames of the car. The 45 side sills 3 are composed of two inverted L-shaped angle bars the horizontal members of which project away from each other, and they are separated and held apart from the free entrance and movement of the lower 50 ends of the doors by the spacing blocks 11 held in place by the bolts or rivets 12. The side frames 13 and 14 of the door opening in the car, are preferably formed of angle bars riveted at their upper ends to the lower 55 flanges of the angle bars 6 and 7, and at their lower ends to horizontal flanges of the

side sill 3. These side frames at each side of the door are separated sufficiently for the free movements of the doors, and also to permit of the free passage of air between 60 the frame and the door for ventilating the car. Where it is necessary or desirable to make the doors air tight, as in refrigerator cars, it can be done by suitable filler strips.

In order to permit of the passage of air 65 from the car to the outer air, or vice versa, I have provided the angle bars 7, of the eaves frame, with openings 14, located at intervals throughout the length of the car through which the air may freely pass from 70 the car into the space between the angle bars 6 and 7 and also from the latter into the car.

While I have shown the car provided with two doors 15 adapted to move away from each other in opening, and toward each other 75 in closing, I may however use a single door such as is now commonly used. The doors 15 each project at the top into the space between the angle bars 6 and 7, and at the bottom into the space between the sill members 3, thus absolutely preventing the possibility of any outward displacement of the door. Each member of the door is provided at its top, near each end, with the oppositely 80 projecting angle plates 16, each of which 85 is provided on its lower face with concaved seats 17 for the roller 18, which latter move on runways on the top faces of the lower flanges of the angle bars 6 and 7.

One member of the door 15 is constructed 90 at its inner edge as shown at 19, Fig. 4, to receive the inner edge of the other member, and said other member is provided with a stop 20 which limits the movements of the door sections toward each other so as to prevent them from becoming wedged together. Each door section is also provided with a handle 21, by which they may be moved to open and closed position, and the two sections are limited in the closing movements 95 100 by the abutment 22 located in the eaves frame and in a position to engage the two members of the door at the top, thus preventing either section of the door from being drawn outwardly sufficiently to create 105 an opening between the door and door frame.

With this construction the doors may be readily and quickly moved to open or closed position. In open position they are 110 closed between the inner and outer walls of the car body, and when in closed position

they are positively retained against any outward dislodgement or swinging movement, by the slotted members of the car frame which receive respectively the upper and lower ends of the doors, and this is true in the event of breakage of any one or more of the roller bearing supports for the doors. Again with this construction the top and bottom sections of the frame are so braced that the load cannot press outwardly and bind the door, and the roof truss prevents any outward movement of the hollow frame at the top.

It is evident that many slight changes might be resorted to in the relative arrangement of parts shown and described without departing from the spirit and scope of my invention. Hence I would have it understood that I do not wish to confine myself to the exact construction and arrangement of parts shown and described but,

Having fully described my invention what I claim as new and desire to secure by Letters-Patent, is:

1. In steel car construction, the combination of a hollow eaves frame carrying the roof of the car, the said eaves frame being composed of two angle bars the lower flanges of which are spaced apart to form an opening for the upper edge of the door whereby the latter will be supported at both sides and side sills composed of angle bars also

spaced apart to receive the lower edge of the door and support the latter at both sides.

2. In steel car construction, the combination of a hollow eaves frame supporting the roof of the car, the said frame being composed of two angle bars the lower flanges of which form supports for the door carrying means and are spaced apart leaving a longitudinal opening for the upper edge of the door whereby the latter will be supported at both sides, side sills composed of angle bars also spaced apart to receive the lower edge of the door and support the latter at both sides, and a door frame intermediate said eaves frame and side sill.

3. In steel car construction, the combination of a hollow eaves frame supporting the roof of the car and having a longitudinal opening in the lower side thereof to receive the upper end of a door, the inner side of said eaves frame having openings whereby the interior thereof is in direct communication with the interior of the car, the said eaves frame forming a housing for door carrying means.

In testimony whereof, I have signed this specification in the presence of two subscribing witnesses.

CHARLES H. ANDRUS.
